DOOR THRESHOLD

Lloyd Stanko, Toledo, Ohio

Application May 20, 1950, Serial No. 163,230

1 Claim. (Cl. 20—64)

1

This invention relates to thresholds, but more particularly to a threshold which is adapted to effect automatically a weather-tight seal with the door when the latter is in its closed position.

An object is to produce a new and improved threshold which has a spring-tensioned floating portion which is urged into weather-tight sealing engagement with the lower edge portion of the door when the latter is in closed position and which is adapted automatically to accommodate itself to irregularities in the edge portion of the door so that even though the lower edge portion of the door is somewhat irregular, nevertheless satisfactory weather-tight joint will be effected between the threshold and the door.

Another object is to produce a threshold which is simple in construction, inexpensive to manufacture, simple to install, and efficiently and satisfactorily seals the lower edge of the door when in closed position even though such edge portion is not entirely straight horizontally and irrespective of the slight differences in the space between the threshold and the door.

Other objects and advantages will hereinafter appear, and for purposes of illustration but not of limitation, an embodiment of the invention is shown on the accompanying drawings, in which

Figure 1 is a fragmentary elevation of the lower edge portion of a door and its frame, and showing the threshold in position of use when the door is in closed position;

Figure 2 is an enlarged vertical sectional view substantially on the line 2—2 of Figure 1; and

Figure 3 is a sectional view similar to Figure 2, but with the door in its open position.

The illustrated embodiment of the invention comprises a door 10 of the usual type mounted for opening and closing swinging movements on an up and down hinge axis, the hinges 11 therefor being suitably connected to the door frame 12. The threshold 13 consists of a longitudinally elongate body portion 14 which may be of suitable metal produced, for example, from castings. The body has upwardly inclined or sloping side walls 15 and a central longitudinally extending channel or cavity 16 which preferably extends throughout the length of the body and has a closed bottom wall 17, the top being open and providing an elongate slot. Opposite side walls of the cavity 16 include a vertically extending wall portion 18 which merges at its upper end with an inwardly inclined wall portion 19 terminating in a vertically inclined wall portion 20 which provides the upper edge or mouth of the cavity.

2

Disposed within the cavity 16 is a floating section 21 which extends throughout the length of the body and has upwardly sloping walls 22 terminating in an apex portion 23. The inclination of the sloping walls 22 corresponds to the adjacent walls 15 of the body portion so that when the floating section 21 is in its uppermost position such as shown in Figure 3, the walls provide a continuation of each other.

10 Adjacent each of the sloping walls or surfaces 22 is a vertically depending wall 24 which corresponds to the wall portions 20 of the body and beneath the vertical wall 24 is an outwardly inclined wall 25 which when in the raised position 15 of the floating section 21, abuts against the inclined or sloping wall 19 of the body portion which serves as a stop surface to limit the upward movement of the floating section. Adjacent the outwardly sloping wall portion 25 are 20 vertically depending wall portions 26 which slide along the vertical wall portions 18 of the body of the threshold.

On the under side of the floating section 21 are a series of cup-shaped sockets 27 into which 25 extend helical coil springs 28, the opposite ends of which abut against the bottom wall 17 of the cavity 16. As shown, there are three coil springs 28 spaced longitudinally from each other and these springs constantly urge the floating section 21 upwardly to its normal position as shown on 30 Figure 3.

In use, it will be understood that when the door is swung from its open to its closed position, the edge portion of the door will ride along the sloping or inclined wall surface 22 of the floating section 21 and thereby cam or force the floating section 21 downwardly, compressing the springs 28. When the door is in its fully closed position as shown in Figure 2, the floating section 21 is 40 depressed but the apex portion 23 is resiliently urged into engagement with the bottom edge of the door, thereby effecting an exceedingly satisfactory weather-tight joint. This weather-tight joint or seal is effected even though the lower 45 edge of the door is inclined or is not a true horizontal edge because the section 21 can float and automatically adjust itself to accommodate variations in the conformation of the door edge portion. It will further be understood that the space 50 between the lower edge of the door and the threshold may vary but in spite of this situation, the floating section 21 of the threshold will be urged into satisfactory weather-tight engagement. It will be understood that the form of the springs 55 and the number may be varied as desired. In

some instances, leaf springs may be used to advantage or if desired, a rubber cushion may be interposed between the floating section and the body of the threshold and satisfactory results will be achieved.

It is to be understood that numerous changes in details of construction, arrangement and operation may be effected without departing from the spirit of the invention especially as defined in the appended claims.

What I claim is:

A threshold comprising an elongate body, elongate upwardly sloping side walls on said body, a centrally disposed channel extending longitudinally throughout the length of said body, a closed bottom wall for said channel, the top of said channel being open thereby to provide an elongate slot, vertically extending side walls for said channel, an inwardly extending wall portion on the upper edge of each vertical wall for constricting the mouth or top of the channel, the free edge portions of said inwardly extending wall being vertically disposed, an elongate rigid bar vertically movable within said channel and extending throughout the length thereof, upwardly and inwardly sloping side walls on said bar meeting to form an apex portion, the slope of the side walls of the bar corresponding to the slope

of the body side walls so that when the bar is in raised position the side walls thereof merge with and form a continuation of the body side walls, vertically disposed wall portions depending from said side walls of the bar generally to conform to said vertically disposed edge portions of the channel, outwardly extending wall portions contiguous to said depending wall portions for abutting against said inwardly extending wall portions of the channel in the raised position of the bar, the under side of said bar having a plurality of sockets spaced from each other, and springs in said sockets respectively and bearing against said closed bottom wall of the channel thereby yieldingly to hold said bar in its raised position.
